(57) **CLAIM**

The ornamental design for a model vehicle bumper as shown and described.

DESCRIPTION

FIG. 1 is an upper, left, rear perspective view of a model vehicle bumper showing our new design;

FIG. 2 is a rear elevation view thereof;

FIG. 3 is a front elevation view thereof;

FIG. 4 is a left side elevation view thereof;

FIG. 5 is a right side elevation view thereof;

FIG. 6 is an upper plan view thereof;

FIG. 7 is a lower plan view thereof;

FIG. 8 is a lower, right, rear perspective view thereof; and, FIG. 9 is a lower, left, front perspective view of the model vehicle bumper.

In the drawings, the broken lines illustrate portions of the model vehicle bumper that form no part of the claimed design.
